UNITED STATES PATENT OFFICE

IRA A. WEAVER, OF SPRINGFIELD, ILLINOIS, ASSIGNOR TO WEAVER MANUFACTURING COMPANY, OF SPRINGFIELD, ILLINOIS, A CORPORATION OF ILLINOIS

VEHICLE LIFTING APPLIANCE

Application filed September 12, 1929. Serial No. 392,103.

My invention pertains to appliances for raising or elevating bodies, such as, automobiles, for inspection or the performance of service work thereon, and concerns more especially, though not restrictedly, certain features of structural and operating advantage in hydraulic and similar hoists.

One object of the invention is to provide an apparatus of this character equipped with at least semi-automatic means for clamping the vehicle to the lifting-rails, so that it will be held securely while in elevated position and without danger of falling off, especially sideways, as it is desirable to make the appliance rather narrow.

A further aim of the invention is to provide adjustable means for lifting the vehicle by the wheels, if so desired, at the same time giving free access to the brake connections, drainage plugs, etc.

Another purpose of the invention is to supply a suitable and convenient hoisting structure in which the lifting plunger and the clamping mechanism specified may be easily removed from the casing that accommodates and supports them, so that it can be inserted and used in a casing on the outside of the building in warm weather and transferred to another casing inside of the building for use during the winter months, or it can be merely stored inside during the colder period, if preferred.

To make the invention clear to those acquainted with this art, a present, preferred embodiment of the invention has been illustrated in the accompanying drawings, forming a part of this specification, and to which reference should be had in connection with the following description, like reference numerals being employed to designate the same structural elements throughout the several views.

In these drawings:—

- Figure 1 is a plan view of the hoist;
 45 Figure 2 is a vertical cross-section on an enlarged scale on line 2—2 of Figure 6;
 Figures 3, 4 and 5 are horizontal sections on lines 3—3, 4—4, and 5—5 of Figure 2;
 50 Figure 6 is a longitudinal section on line 6—6 of Figure 1;

Figure 7 is an enlarged cross-section on line 7—7 of Figure 6;

Figure 8 is a cross-section on an increased scale on line 8—8 of Figure 6; and

Figure 9 is an end elevation as indicated by 55 the arrow 9 in Figure 6.

Referring to these drawings, and particularly to Figure 2 thereof, it will be observed that an upright casing or cylinder 11 is sunk into the ground with its upper end practically flush with the surface of the ground or floor, the lower end of such hollow element being closed.

Vertically-spaced guide-bearings 13 and 14 for the hollow plunger 15 are desirably lined with brass, or other suitable metal, the upper ring bearing 13 having a top, outstanding flange of slightly larger diameter seated on a ledge on the inside of the casing and held in place by a split snap ring 16 occupying a 60 groove or channel on the inside of the casing, another ring 17 fitting inside of such locking 65 ring 16 to hold it in its groove and at the same time to form a level surface for the plunger packing-ring 18 to bear on, such packing 70 75 18 being held in place by the usual packing-gland 19 held on the top of the cylinder by the customary screws 21, 21.

The lower bearing-ring 14 is positioned by indentations 20 in casing 11 and the two bearing rings 13 and 14 are connected together by a plurality of bars 30 welded or otherwise secured to both, so that the bearing structure constitutes a unit.

The oil or other suitable liquid for operating the hoist is admitted and discharged through a valve-controlled pipe 23 fitted with a supplementary-valve 24 of known structure which allows free entrance of the liquid therethrough while the hoist and load is being elevated but which forms a restriction on the discharged liquid, whereby to lower the load at a substantially predetermined speed regardless of the weight of the load.

Plunger 15 has the web of an inverted section of channel 25 welded to it and closing its upper end, and a pair of I-beam lifting-rails 26, 26 are bolted to the depending flanges of the channel with interposed, reinforcing strips or plates 27, 27.

To further strengthen and stiffen the structure, a plate 28 is employed between the plunger and the channel flanges, being welded to both.

5 The mechanism for locking the vehicle on the hoist comprises the following specified cooperating parts.

The bottom wall 29 of the plunger has the open end of a pipe 31 extended down through it, the upper part of the pipe being bent to project through the side of the upper portion of the plunger and connected to the interior of one end of a small, transverse cylinder 32 mounted on the rails and internally accommodating a slidable piston 33 fitted with a concave or cup-shaped, central, bearing surface 34 operating with the curved or rounded end of a connecting-rod 35 rockingly joined at 36 to the end of a crank arm 37 fixed 10 on a square shaft 38 oscillatory in bearings 39, 39 mounted on one of the lifting bars.

Obviously, oil under pressure entering the cylinder forces the piston along and rocks the square shaft, the piston being equipped 25 with a coiled spring 41 which automatically returns it to original position as soon as the pressure on the oil is released.

An arm 42 is slidably mounted on shaft 38 and its free end has an oblique hook 43 more 30 or less loosely hinged thereon, such hook having a relatively-long handle 44 by which it may be easily manipulated by the operator.

The purpose of the angular disposition of the hook and its somewhat loose mounting is 35 to permit the hook to enter between the steering-rod and axle of the automobile and then be brought in line over the front axle.

In order that the two plunger bearings may 40 be slid out of the casing automatically upon the upward withdrawal therefrom of its plunger, the latter, at its lower end, is equipped with a cross-bar 45 whose ends project beyond the cylindrical surface of the plunger, as shown in Figure 2, so that when 45 the plunger is pulled upwardly out of the casing, such ends will engage the under side of the lower bearing and raise both of them, due to their interconnection, out of the casing, whereby the abnormal or withdrawal 50 action of the plunger automatically displaces cent of the plunger automatically displaces its bearings for removal at the same time.

To support the rear-axle housing of the automobile on the hoist, an appropriately-formed, skeleton frame 46 is made to rest on 55 the lower, inner flanges of the I-beam lifting-bars.

Such frame may be welded, riveted or bolted in fixed position on the lifting-bars or it may be left free to slide thereon.

60 The operation of the apparatus so far described is practically as follows:—

Assuming that the plunger is in its lowermost position and that the lifting-bars are on or substantially on the floor or ground, the

65 automobile to be raised is driven astride the

lifting-bars until its rear-axle housing is in register with the frame 46, or the latter is shifted along on the bars until it is in proper place beneath such housing.

Then the operator by means of handle 44 70 moves arm 42 and its hook along on shaft 38 until they are in correct position and then manipulates the hook until it is located above the front axle.

Whatever rocking of the shaft 38 may be 75 required to effect this result is readily accomplished because the connecting-rod 35 is not directly, but rather loosely, associated with the bearing 34 of piston 33.

Thereupon, oil under substantial pressure 80 is admitted into the casing through pipe 23 and valve 24, but, before the plunger begins to ascend, enough of such admitted oil flows through pipe 31 into cylinder 32 to cause its piston to slide therein sufficiently to pull the hook 43 down firmly on to and in holding or clamping relation on the front axle of the automobile about to be lifted, which bearing it will maintain.

Continued inflow of oil causes the elevation 90 of the plunger and its companion lifting-bars, the automobile beginning its ascent as soon as the bars contact with the underside of the front axle and the frame 46 engages the rear-axle housing.

So long as the load remains on the hoist, the oil below the plunger will be under pressure and that assures a similar liquid pressure in cylinder 32 maintaining its piston in outward position against the action of spring 41, thus making positive the continued clamping 100 of the vehicle, which prevents it from accidentally sliding or tipping off of the supporting hoist.

As soon as the lifting appliance has descended to its original position by the oil flowing out of the cylinder, and not until then, because of the retarded or restricted outflow of such oil through the valve, the piston 33 under the expanding action of its spring returns automatically to its initial hook-releasing position, enabling the operator to withdraw the hook manually and allowing the vehicle to be driven off of the hoist.

110 It will be observed that this hoist is comparatively narrow and for that reason the clamping hook is of especial value in preventing the vehicle from toppling off of the appliance sidewise.

115 By lifting the automobile in the manner specified, all four wheels are free to turn and hence their brakes can be conveniently tested and adjusted.

If it be desired to lift the back end of the 125 vehicle by its rear wheels, to render the differential more accessible for draining its oil or for repair work thereon, a supplemental means is used.

This comprises a frame 51 composed of 130

two, spaced frames 52, 52 connected together at their outer ends by horizontal upwardly-flaring bars 53, 53, the center portions of the frames having apertures which receive the pair of lifting-bars, uprights 54, 54, preventing the frame as a whole from shifting sideways of the hoist.

When this added frame 51 is applied or slid on to the hoist, as shown, the frame 46 may be removed, or left in place or moved 10 along the lifting-bars out of the way, and when the vehicle is driven astraddle the hoist, the rear wheels roll on to the outstanding frame bars 52, 52 and are precluded from slipping off of them by the retaining bars 15 53, 53.

The front axle having been clamped as above outlined, as the hoist ascends, the back part of the vehicle rises somewhat first because it is supported on the appliance by the 20 rear wheels, but soon thereafter the lifting-bars engage, and raise the front of the automobile through the front axle, the car as a whole sloping downwardly, forwardly a little.

The service work on the car having been completed, the hoist is lowered automatically releasing the clamping hook and allowing its manual detachment, and then the car 30 may be driven off of the apparatus.

One embodiment only of the invention has been presented, but it is susceptible of a variety of commercial forms, and many modifications may be incorporated in the one 35 set forth without deviation from the fundamental principles of the invention, as defined by the appended claims, and without the surrender of any of its material advantages.

The adjustment lengthwise of the hoist of 40 the front axle clamp, the differential support, and the rear wheel extension member readily adapts the apparatus for convenient use with vehicles of varying lengths of wheel base, and whatever adjustments are needed can be 45 easily made with dispatch and convenience.

I claim:

1. In a hoist, the combination of an upright cylinder, a plunger slideable in said cylinder, load lifting and lowering means carried by said plunger, means to admit an operating fluid into said cylinder and to permit its discharge therefrom to reciprocate said plunger, a guide-bearing supported in said cylinder for said plunger, and means to remove said guide-bearing from said cylinder by the removal therefrom of said plunger.

2. In a hoist, the combination of an upright cylinder, a plunger slideable in said cylinder, load lifting and lowering means carried by said plunger, means to admit an operating fluid into said cylinder and to permit its discharge therefrom to reciprocate said plunger, a plurality of guide-bearings supported in said cylinder for said plunger

spaced apart vertically and connected together, and means to remove said guide-bearings from said cylinder by the removal of said plunger therefrom.

3. In a vehicle-hoist, the combination of a support for the vehicle, means to raise and to lower said support, means to clamp the vehicle to said support, and means actuated automatically substantially simultaneously with the lowering means to work said vehicle clamp.

4. In a vehicle-hoist, the combination of a support narrower than the distance apart of the front or rear wheels of the vehicle to be elevated, means to raise and to lower said support, means to clamp the vehicle to said support, and means to render said clamp automatically active during the elevation and descent of said support and vehicle.

5. In a vehicle-hoist, the combination of a support for a vehicle, means to raise and to lower said support, means to clamp the vehicle to said support, and means to render said clamp automatically active just prior to the institution of the support rise and to maintain said clamp active until the support has again returned substantially to its lowest position.

6. In a vehicle-hoist, the combination of an upright cylinder, a plunger reciprocatory therein, a vehicle support on said plunger, a vehicle-clamp on said support, means to control the flow of operating fluid into and out of said cylinder to raise and to lower said plunger, support and vehicle thereon, and fluid-actuated means to operate said clamp governed automatically by the control of said cylinder fluid.

7. In a vehicle-hoist, the combination of an upright cylinder, a plunger reciprocatory therein, a vehicle support on said plunger, a vehicle-clamp on said support, means to control the flow of operating fluid into and out of said cylinder to raise and to lower said plunger, support and vehicle thereon, and a fluid-actuated means to operate said clamp connected to the interior of said cylinder to be governed by the fluid therein.

8. In a vehicle-hoist, the combination of a support, means to raise and to lower said support, means adjustable lengthwise said support adapted to engage and to lift the rear portion of an automobile, said support being designed to engage and lift the front axle of the automobile, and a vehicle-clamp on and adjustable lengthwise of said support and adapted to clamp the front axle of the vehicle.

9. In a vehicle-hoist, the combination of a support narrower than the distance between the two front or the two rear wheels of a vehicle, a frame on said support wide enough to support the two rear wheels of the vehicle, and means to raise and to lower said support, whereby the vehicle will be elevated

through contact of said frame with its rear wheels and of said support with its front axle.

10. In a vehicle-hoist, the combination of a support narrower than the distance between the two front or the two rear wheels of a vehicle, a frame on and adjustable lengthwise of said support wide enough to support the two rear wheels of the vehicle, and means to raise and to lower said support, whereby the vehicle will be elevated through contact of said frame with its rear wheels and of said support with its front axle.

11. In a vehicle-hoist, the combination of a support narrower than the distance between the two front wheels or the two rear wheels of a vehicle, a frame on and adjustable lengthwise of said support and wide enough to support the two rear wheels of the vehicle, power means to raise and to lower said support, whereby the vehicle will be elevated in slightly tipped condition through contact of said frame with its rear wheels and of said support with its front axle, a clamp on said support for the front axle of the vehicle, and means to operate said clamp from said power means.

In witness whereof I have hereunto set my hand.

30 IRA A. WEAVER.
